W. F. SCHULZ

FOUNDRY FLASK

Filed Sept. 9, 1922

Inventor
W. F. Schulz.

By his Attorneys

Markel Clark

UNITED STATES PATENT OFFICE.

WALTER F. SCHULZ, OF SHARON, PENNSYLVANIA, ASSIGNOR TO TRUSCON STEEL COMPANY, OF YOUNGSTOWN, OHIO, A CORPORATION OF MICHIGAN.

FOUNDRY FLASK.

Application filed September 9, 1922. Serial No. 587,041.

To all whom it may concern:

Be it known that I, WALTER F. SCHULZ, citizen of the United States, residing at Sharon, county of Mercer, and State of Pennsylvania, have invented certain new and useful Improvements in Foundry Flasks, of which the following is a specification.

This invention relates to foundry flasks, and more particularly to foundry flasks formed of pressed steel sections.

The object of the invention is to provide an improved form of flask member which is of double walled construction whereby the outer surface of the flask is maintained at a lower temperature than would otherwise be possible and which possesses great strength and rigidity and is particularly useful in the production of very rigid flasks of large size but of comparatively shallow depth.

With this object in view, the invention consists in the features of construction and arrangement hereinafter more fully described and clearly set forth in the claims appended hereto.

A complete flask usually consists of two substantially similar flask members, namely, a cope member and a drag member. For convenience of illustration, only one flask member has been illustrated in the accompanying drawings according to one particular embodiment of the invention, and the description thereof is applicable to either flask member.

In the accompanying drawing,

Figure 1 is a plan view of an improved flask member constructed in accordance with the present invention, one-half of the view being a section taken on the line I—I of Figure 2,

Figure 2 is a side elevation of the flask member shown in Figure 1,

Figure 3 is an end elevation of this flask member, and

Figure 4 is an enlarged cross-sectional view taken on the line IV—IV, Figure 1.

The flask member comprises an outer wall 1 and an inner wall 2 spaced therefrom and substantially parallel therewith. These walls in the particular flask member illustrated are of rectangular configuration in plan, as clearly shown in Figure 1, although

the invention is not restricted to this particular shape or configuration as other shapes may be employed. Each of these walls is preferably composed of a plurality of sections which are suitably joined together as, for example, by welding the abutting ends of the sections. It is preferable, particularly when the flask member is of large size, that the joints between the sections of one wall should be located a substantial distance from the joints between the sections of the other wall. This is clearly indicated in Figure 1 in which the numeral 3 indicates the joints between the sections of the outer wall and the numeral 4 indicates the joints between the sections of the inner wall. It will be understood that the middle portion of the flask as shown in Figures 1 and 2 is broken away for convenience of illustration and that the joints 3 and 4 in the side portions of the walls are spaced apart a materially greater distance in the actual construction than appears in these figures.

The outer wall 1 as shown more clearly in Figure 4 is of channel section comprising the web 5 and the inwardly projecting flanges 6 and the inner wall 2 is positioned between the flanges 6 in spaced relation to the web 5 of the wall 1. The upper and lower edges of the wall 2 may if desired be welded to the flanges 6 either continuously or in spots, as indicated at 7. Preferably, the flanges 6 extend beyond the inner wall as indicated at 8 to provide sand retaining ledges.

The inner wall 2 is held in spaced relation to the outer wall 1 by means of embossed or outwardly pressed portions 9 which are shown of truncated conical form and the outer portions of which are in engagement with the inner surface of the web 5. Where a plurality of rows of these embossed portions 9 are provided they are preferably arranged in staggered relation as clearly shown in the drawings. The embossed portions 9 of the inner wall may be secured rigidly to the web of the outer wall by suitable securing devices such as rivets 10.

The embossed portions 9 not only serve to hold the inner and outer walls in spaced relation and to provide a place to fasten the two walls rigidly together but they also

serve to provide a plurality of sand retaining pockets upon the inner surface of the inner wall.

It will be understood that the double walled construction provided by the arrangement of the inner and outer walls in the manner described cannot be distorted without the inner and outer walls moving with reference to one another and such relative movement is positively prevented not only by the rigid connection of the walls together but by the relative arrangement of these walls in the manner stated. The double walled construction, in addition to imparting great strength and rigidity to the flask member, also provides for the maintenance of the outer wall of the flask at a lower temperature than would otherwise be possible.

The flask member illustrated is provided with lifting trunnions 11 which trunnions project through apertures in the outer wall 1 into engagement with the inner wall 2 and are welded to both walls, thereby firmly securing these trunnions in place. The brackets 12 for the dowel pins or sockets therefor as usually provided, are also preferably passed through openings in the outer wall into engagement with the inner wall and welded to both walls so as to provide a secure and rigid connection for these brackets.

It is to be understood that the invention is not restricted to the particular details of construction hereinbefore described as the same may be modified within the scope of the claims appended hereto.

What I claim and desire to secure by Letters Patent is:

1. A flask member, comprising an outer wall, and an inner wall substantially parallel to and spaced apart from said outer wall and rigidly secured thereto.

2. A flask member, comprising an outer wall, and an inner wall substantially parallel to and spaced apart from said outer wall and having portions extending from the plane of the wall into engagement with said outer wall and rigidly connected therewith.

3. A flask member, comprising an outer wall of channel cross-section having inwardly projecting flanges, and an inner wall spaced apart from said outer wall, and secured in place between the inwardly projecting flanges thereof.

4. A flask member, comprising an outer wall of channel cross-section having inwardly projecting flanges, and an inner wall spaced apart from said outer wall and positioned between the inwardly projecting flanges thereof, and having portions extending into engagement with the web of said outer wall and secured thereto.

5. A flask member, comprising an outer

wall of channel cross-section having inwardly projecting flanges, and an inner wall spaced apart from said outer wall and positioned between and secured to the inwardly projecting flanges thereof.

6. A flask member, comprising an outer wall of channel cross-section having inwardly projecting flanges, and an inner wall spaced apart from said outer wall and positioned between and welded to the inwardly projecting flanges thereof.

7. A flask member, comprising an outer wall of channel cross-section having inwardly projecting flanges, and an inner wall spaced apart from said outer wall and positioned between and secured to the inwardly projecting flanges thereof, and having portions extending into engagement with the web of said outer wall and secured thereto.

8. A flask member, comprising an outer wall of channel cross-section having inwardly projecting flanges, and an inner wall spaced apart from said outer wall and positioned between the inwardly projecting flanges thereof, said inner wall having embossed portions engaging and secured to the outer wall and forming sand retaining pockets.

9. A flask member, comprising an inner wall and an outer wall, one of said walls being of channel cross-section and the other being substantially planar and secured to the first wall to form an enclosed space between said walls.

10. A flask member, comprising an inner wall and an outer wall, one of said walls being of channel cross-section and the other being substantially planar and secured to the first wall and fitting between the flanges thereof to form an enclosed space between said walls and flanges.

11. A flask member, comprising an inner wall and an outer wall, one of said walls being of channel cross-section and the other being substantially planar and secured to the first wall to form an enclosed space between said walls, one of said walls having embossed portions pressed out of the plane thereof and engaging the other wall to space said walls apart.

12. A flask member, comprising an inner wall and an outer wall, secured together in spaced relation, and substantially uniformly spaced apart throughout, and co-acting to form an enclosed space therebetween.

13. A flask member, comprising an inner wall and an outer wall, secured together in spaced relation, and co-acting to form an enclosed space therebetween, at least one of said walls having flanges at substantially right angles thereto and engaging the other wall.

14. A flask member, comprising an outer wall, and an inner wall secured thereto, at least one of said walls having numerous rela-

tively small embossed portions extending toward and in engagement with the other wall to hold said walls in substantially uniform spaced apart relation at all points.

5 15. A flask member, comprising an outer wall, and an inner substantially planar wall secured thereto, said inner wall having numerous relatively small embossed portions extending toward and in engagement with the outer wall to space said walls apart and to form sand retaining pockets.

10 16. A flask member, comprising an outer wall, and an inner wall, at least one of said walls having numerous relatively small embossed portions extending toward and in engagement with the other wall to space said walls apart throughout the entire extent thereof and means securing said embossed portions to said other wall.

15 17. A flask member, comprising an outer wall, an inner wall spaced apart from said outer wall, and lifting trunnions welded to both of said walls.

20 18. A flask member, comprising an outer

wall, an inner wall spaced apart from said outer wall, and dowel pin brackets welded to both of said walls.

19. A flask member, comprising an outer wall, and an inner wall spaced apart from said outer wall, each of said walls comprising a plurality of sections joined together, with the joints of one wall located a substantial distance from the joints of the other wall.

20. A flask member, comprising an outer non-corrugated wall, and an inner non-corrugated wall, said walls being secured together in spaced apart relation at substantially all points to provide a single enclosed space extending all around between said walls.

In testimony whereof I affix my signature in presence of two witnesses.

WALTER F. SCHULZ.
